UNITED STATES PATENT OFFICE.

ALBERT DUDLY, OF MENOMINEE, MICHIGAN.

DESIGN FOR A WRENCH-STOCK.

SPECIFICATION forming part of Design No. 35,421, dated December 10, 1901.

Application filed June 15, 1901. Serial No. 64,758. Term of patent 14 years.

To all whom it may concern:

Be it known that I, ALBERT DUDLY, a citizen of the United States, residing at Menominee, in the county of Menominee and State 5 of Michigan, have invented and produced a new and original Design for a Double-Head Wrench-Stock; and I do hereby declare the following to be a full, clear, and exact description of the invention, such as will enable 10 others skilled in the art to which it appertains to make and use the same, reference being had to the accompanying drawings, forming part thereof.

In the said drawings, Figure 1 represents 15 a side elevation, and Figs. 2, 3, and 4 are detail sectional views taken, respectively, on the lines 2 2, 3 3, and 4 4 of Fig. 1, of a wrench-stock embodying my new design.

My design relates to the new and original 20 shape or configuration of the article.

The leading or essential feature consists in the unitary design for a wrench-stock made 25 the subject of illustration, comprising the peculiar and novel shape of the handle part A, of the same width its entire length, save that it is rounded at its lower or outer end and formed with a series of square-sided and round-bottomed recesses b b b in one edge thereof, the upper half of said part A having 30 otherwise flat edge surfaces c c on each side, while both edges of the lower half of said part A are rounded, as shown at i i, together with the peculiar and novel shape of the head part B, extending an equal distance on each side 35 of the handle part A and formed with lower oblong rectangular flat-faced portions f f at each side of greater width or thickness than

that of the handle part A and an upper portion or crown h of less width or thickness than that of said handle part A, said upper 40 portion h being centrally and convexly rounded on the arc of a circle between the points m m and thence descending in straight lines of equal length on each side to the points n n, in line with the vertical straight 45 flat outer ends g g of the described portions f f, the upper edge of this upper portion or crown of the head part B being transversely rounded on a convex circular line, as shown at i'.

Minor features of my said design comprise the central longitudinal side flutes d d in the handle part A, extending continuously to the crown or upper portion h of the head part B, leaving the center of said handle part A and 50 the crown h of the same thickness and separating the described portions f f of the said head part B, with longitudinal concavities j j at each side of said flutes d d, the transverse serrated recesses e across the under side of 55 one of the head portions f, and the longitudinal concave surfaces j' j' above the described portions f of the head part B.

Having thus described my invention, what I claim as new, and desire to secure by Letters 60 Patent, is—

The design for a wrench-stock, substantially as herein shown and described.

In testimony whereof I affix my signature in presence of two witnesses.

ALBERT DUDLY.
